Whittemore & Hulbert**[57] CLAIM**

The ornamental design for a water game column, as shown.

DESCRIPTION

FIG. 1 is a front elevational view of the water game column;
FIG. 2 is a side elevational view of the water game column,
the opposing side elevational view being identical thereto;
FIG. 3 is a rear elevational view of the water game column;
FIG. 4 is a top plan view of the water game column; and,
FIG. 5 is a reduced perspective view of the water game
column.
